S. GADE

WASTE AND OVERFLOW FIXTURE FOR BATHTUBS

Filed Sept. 19, 1925

SAMUEL GADE
INVENTOR

BY *Walter E. Woodhull*
ATTORNEY

UNITED STATES PATENT OFFICE.

SAMUEL GADE, OF NEW YORK, N. Y.

WASTE AND OVERFLOW FIXTURE FOR BATHTUBS.

Application filed September 19, 1925. Serial No. 57,385.

To all whom it may concern:

Be it known that I, SAMUEL GADE, a citizen of the United States, and a resident of New York, in the county of New York and State of New York, have invented certain new and useful Improvements in Waste and Overflow Fixtures for Bathtubs, of which the following is a specification.

This invention relates to connected waste and overflow fixtures for bath tubs of the type which are concealed behind the wall of the tub and customarily located within the wall of masonry work adjacent thereto.

It is one of the objects of the invention to provide for the withdrawal of the waste valve and its operating members through, respectively, the waste opening and the overflow opening of the fixture, without necessitating the breaking open of the wall adjacent the tub and dismembering the fixture to insert the same.

Another object is to provide for a construction at the overflow end of the fixture wherein the operating handle and the valve operating mechanism may be withdrawn for purposes of adjustment or replacement without breaking the joint between the overflow pipe and the tub.

A still further object is to make a fixture of this type self-draining, eliminating the accumulation of sediment and other foreign matter.

Still other objects will become apparent in the following specification and the accompanying drawings, in which—

Fig. 1 is a vertical longitudinal sectional view through the fixture, with the waste valve in an open or draining position;

Fig. 2 is a similar sectional fragmentary view of the waste valve end of the fixture, showing the valve in a closed position;

Fig. 3 is a horizontal sectional view along the plane of line 3—3, in Fig. 1;

Fig. 4 is a fragmentary horizontal sectional view along the plane of line 4—4 in Fig. 1;

Fig. 5 is an elevational view of the overflow and valve operating handle mechanism.

Fig. 6 is a fragmentary vertical sectional view of the overflow end of the fixture, but showing the operating handle mechanism removed therefrom;

Fig. 7 is an elevational view of the regulating means for the operating member of the valve;

Fig. 8 is an elevational view of the overflow end of the fixture as shown in Fig. 6; and

Fig. 9 is a side view of the valve operating cam mechanism and its support.

Like numbers of reference denote similar parts throughout the several views and the following specification.

10 is a bath tub which is of the usual construction and has an upwardly extending wall 11. 12 is an opening through the wall 11 of the tub near its top. At the rear of wall 11 is an elbow 13 having a lip 14 extending into the opening 12, an annular flange 14^a surrounding the lip and fitting tightly against the rear side of wall 11. 15 is a ring disposed around opening 12 at the front side of the wall 11, provided with inwardly projecting lugs 16 and 17. 18 and 18^a are screws which, passing through holes in lugs 16 and 17, are screwed into lugs 19 and 19^a at the inside of elbow 13, thereby securely fastening the elbow to the wall 11 around the opening 12.

20 is an overflow pipe secured vertically at its upper end to the elbow 13 and at its lower end to a T 21. 22 is an elbow fastened to the underside of the bottom of the tub 10 by means of a sleeve 23, in threaded engagement with elbow 22 at 24. The top of sleeve 23 is bored out interiorly at 25 and its bottom is somewhat smaller at 26, constituting a drain passage. 27 is a tapered seat for a valve 28 slidably disposed within the bore 26.

Valve 28 has a head 29 provided with a seat corresponding with seat 27 in the sleeve 23 and with downwardly extending ribs or guides 30. 31 is a strainer plate covering the drain passage and preventing the valve 28 from extending into the tub proper.

At its bottom, the valve 28 has a set screw 32 provided with a rounded head 33 and a lock nut 34 for the purpose of adjusting the lift of the valve, as will be more apparent hereinafter.

35 is a bracket having a threaded stud 36 screwed into the inside of elbow 22 at its bottom, and arms 37 forming a slot 38 between them. Arms 37 are slotted obliquely at one side only at 39.

40 is an eccentric disc or cam having hubs 41 at both sides and a shaft 42 integrally with it. 43 is a lug extending downwardly away from the disc 40 at approximately 90 degrees from its major portion. The shaft 42 rests at the bottom of the obliquely disposed slots 39 of the bracket 35. 44 is a bore through the lug 43.

45 is a drain pipe, horizontally disposed, 10 connecting elbow 22 with T 41. 46 is an outlet pipe leading from the bottom branch of T 21 to the sewer pipe connection of the house.

47 is an overflow shield, substantially cup-shaped, having its sides 48 fit over the ring 15 against the wall 11 of the tub 10. At the lower half of its face, overflow shield 47 has slots 49, and its lower side has recesses 50 and 51. Between these recesses is a somewhat thickened portion forming a lug 52 which fits into a recess 15^a at the bottom of the ring 15, for the purpose of keeping the recesses of the shield in evenly spaced relation to the wall of the tub. Overflow shield 25 47 is securely fastened to the inside of elbow 13 by means of screws 53 and 54 which are in threaded engagement with lugs 19 and 19^a. Above the slots 49, shield 47 has an inwardly extending tubular extension 55, 30 56 is an operating lever having a handle 57 extending into the tub and a rod 58 into the elbow 13. 59 is a ball-shaped portion at the center of the lever 56 being held in fluid tight contact with shield 47 by means of a 35 nut 60 at one side and a spring 61 at its other side, forming the usual ball joint known as such in the art.

Suspended from the extreme end of rod 58 of lever 56 is a turn buckle 62 which consists of a sleeve portion 63 having at one end a bore 64^a through which the rod 58 is passed which is provided with suitable pins 64 and 65 to prevent accidental loss of the turn buckle, and a link 66 in threaded engagement with the other end of the turn buckle. A lock nut 67 is provided to secure the link 66 to the turn buckle 62 in any desired adjusted position. 68 is a chain (shown diagrammatically only by a dotted line) connecting the link 66 with the downwardly extending lug 43 of the eccentric disc 40 within the elbow, to which it is fastened by being passed through its bore 44. The chain 68 is led past a roller 69 rotatably mounted upon a shaft 70 within the T 21, about in line with the top of the horizontal drain pipe 45.

The operation of the waste and overflow fixture embodying the principles of my invention, is as follows:

Elbow 13 is secured to the opening 12 of the tub by means of ring 15, screws 18 and 18^a engaging the elbow, as shown in Fig. 6. The elbow 22 with bracket 35, preferably, 65 fastened therein, is connected to the under-

70 side of the tub by means of sleeve 23, as explained above. Pipes 20 and 45 are then cut to the right lengths and placed in position with T 21 which latter is connected to the outlet pipe 46. All this is done before the masonry work or walls of the bath room are completed, which can then be finished. In this manner, all bath tubs in an apartment house may be set up with their piping and all masonry work finished.

75 In order now to complete the installation, I take the overflow shield 47 with its lever 56 and turn buckle 62 fastened thereto with chain 68 and eccentric disc 40 and screw it, around the ring 15, to the elbow 13 by means of screws 53 and 54, letting the disc 40 and chain 68 drop down through the elbow and pipe 20 to extend somewhat into the pipe 46. I then insert a suitably bent hook made of wire through sleeve 23 and pipe 45 until I catch the downwardly hanging chain 68 and draw it with the eccentric disc 40 through pipe 45 into the elbow 22, where I slip the shaft 42 of the disc into the obliquely disposed slots 39 of the bracket 35, with the major portion of the eccentric disc projecting upwardly, as shown in Fig. 1. The valve 28 is then placed within sleeve 23 and the strainer plate 31 fastened over it. With the various parts assembled, as shown 90 in Fig. 1, it is clearly evident that any water in the tub will be discharged through the strainer 31, sleeve 23, valve opening 26, elbow 22, pipe 45, into the outlet pipe 46. By giving the handle 57 of the lever 56 an upward position, the chain 68 will loosen its tension on eccentric disc 40 and permit 95 by gravity the same to assume the position indicated in Fig. 2 where owing to the eccentricity of the disc 40, the valve 28 is allowed to come to its seat 27 within the sleeve 23, thereby closing the water passage. Water will then fill the tub, until the supply is cut off or until its level reaches the overflow slots 49 and recesses 50 and 51 in the overflow shield, when it overflows through 100 elbow 13 and pipe 20 into outlet pipe 46.

105 The lift of the valve 28 can be regulated by adjusting the set screw 32 and nut 34. Tightness of the chain 68 and its proper tension on the eccentric disc is insured by adjustment between the turn buckle 62 and link 66. The roller 69 serves the purpose of 110 eliminating unnecessary friction between the pipes and the chain 68.

115 When it is desired to readjust the tension of the chain, or to take the working parts of the fixture out for inspection or repair, it is not necessary, as in the usual constructions heretofore provided, to break the connection between the overflow pipe and the bath tub, but only the screws 53 and 54 need be removed which permits the entire overflow shield 47 to be withdrawn together with 120 its entire operating lever mechanism, chain 125

and eccentric disc, the latter having previously been lifted out of bracket 35 manually through the waste opening.

It is clearly obvious that the assemblage 5 and removal of the entire valve mechanism can be effected without disturbing the masonry work in the bath room, or the connections of the various pipes with each other or the tub. Furthermore, the valve 28 being 10 located in the highest point of the waste passage below the tub, results in the absence of water trapped in the waste pipe which therefore are self-draining, preventing accumulation of sediment or other foreign 15 matter.

While I have shown and described a preferred embodiment of my invention, I do not wish to limit myself to the particular construction disclosed. It is obvious that 20 various changes of form, proportion, minor details and combination of parts may be resorted to without departing or sacrificing any of the advantages of the invention, as defined in the appended claims.

25 What I claim as new, is:

1. In a waste and overflow fixture for bath tubs, a waste chamber having a water passage in communication with the bottom of a bath tub, an overflow housing, a clamping member at the inside of the tub, fixedly securing the said housing to an outer side wall of the said tub around an overflow opening, pipes leading from, respectively, the said waste chamber and the said overflow housing to an outlet pipe, a valve to close the water passage between the said tub and waste chamber, and an overflow shield carrying mechanism for operating the said valve, detachably secured at the inside of the 30 said wall of the tub and around the said overflow opening directly to the overflow housing, independently of the said clamping member.

2. In a waste and overflow fixture for 45 bath tubs, a waste connection at the bottom of the tub, and an overflow connection at a side wall of the tub, pipes leading from the said waste and overflow connections to an outlet pipe, valve means to shut off the said 50 waste connection from the said tub, the said overflow connection comprising an elbow at the outside of the said wall of the said tub around an overflow opening, a ring at the inside of the tub, means fastening the 55 said ring to the said elbow whereby the same is clamped fluid-tightly against the tub around the overflow opening, and an overflow shield carrying mechanism for operating the said valve, detachably secured at 60 the inside of the tub directly to the said elbow, independently of the said ring.

3. In a waste and overflow fixture for 65 bath tubs, a waste chamber having a water passage in communication with the bottom of a bath tub, an overflow housing, a clamp-

ing member at the inside of the tub, fixedly securing the said housing to an outer side wall of the said tub around an overflow opening, pipes leading from, respectively, the said waste chamber and the said overflow housing to an outlet pipe, a valve to close the water passage between the said tub and waste chamber, insertable into the said waste chamber through the said water passage, and an overflow shield carrying mechanism for operating the said valve, detachably secured at the inside of the said wall of the tub and around the said overflow opening directly to the overflow housing, independently of the said clamping member. 70

4. In a waste and overflow fixture for bath tubs, a waste chamber having a water passage in communication with the bottom of a bath tub, an overflow housing, a clamping member at the inside of the tub, fixedly securing the said housing to an outer side wall of the said tub around an overflow opening, pipes leading from, respectively, the said waste chamber and the said overflow housing to an outlet pipe, a valve to close the water passage between the said tub and waste chamber, and an overflow shield carrying mechanism for operating the said valve, detachably secured at the inside of the 80 said wall of the tub and around the said overflow opening directly to the said overflow housing, independently of the said clamping member, the said mechanism for operating the said valve consisting of a lever handle movably fastened within the 85 said overflow shield, an eccentric disc oscillatorily anchored below the said valve, and an adjustable flexible connection between the said lever handle and eccentric disc, whereby the position of the said disc may be varied for the purpose of raising and lowering the said valve. 90

5. In a waste and overflow fixture for 100 bath tubs, a waste connection at the bottom of the tub, and an overflow connection at the side wall of the tub, drain pipes leading from the said waste and overflow connections to an outlet pipe, the said waste connection comprising an elbow below a waste opening at the bottom of the tub, a sleeve inserted through the waste opening in threaded engagement with one end of the 105 said elbow having a restricted opening provided with a valve seat for the passage of waste water, a valve adapted to close the said restricted opening, one of the said drain pipes being connected to the other end of the said elbow, an eccentric disc suitably journaled within the said elbow and below the said valve, adapted to raise the valve by its eccentricity, and means to rotate the said disc permitting the valve to drop and close the restricted opening in the said sleeve, the 110 said eccentric disc being adapted to be drawn into the said elbow through the said 115

drain pipes and placed in position within the elbow by manipulation through the said sleeve.

6. In a waste and overflow fixture for bath tubs, a waste connection at the bottom of the tub, and an overflow connection at a side wall of the tub, the said overflow connection comprising an overflow elbow at the outside of the side wall of the tub around 10 an overflow opening, a ring at the inside of the tub, means fastening the said ring to the said overflow elbow, and an overflow shield detachably secured at the inside of the tub directly to the said overflow elbow, 15 drain pipes leading from the said waste and overflow connections to an outlet pipe, the said waste connection comprising a waste elbow below a waste opening at the bottom of the tub, a sleeve inserted through the 20 waste opening in threaded engagement with one end of the said waste elbow having a restricted opening provided with a valve seat for the passage of waste water, a valve adapted to close the said restricted opening, 25 one of the said drain pipes being connected to the other end of the said waste elbow, an

eccentric disc suitably journaled within the said waste elbow and below the said valve adapted to raise the valve by its eccentricity, the said overflow shield carrying a lever 30 handle movably fastened within the said shield, and an adjustable flexible connection between the said lever handle and the said eccentric disc adapted to rotate the said disc permitting the said valve to drop and close the restricted opening in the said sleeve, the said eccentric disc at the end of the said flexible connection being insertable through the said overflow opening and adapted to be drawn into the said waste 40 elbow through the said drain pipes and placed in position within the waste elbow by manipulation through the said sleeve, and a roller rotatably mounted within one of the drain pipes for the purpose of preventing frictional contact between the said flexible connection and the walls of the said drain pipes and their connections.

In testimony whereof I have hereunto set my hand.

SAMUEL GADE.
